CONTAINER CLOSURE

Harold B. Hemb, Wilmette, Ill.

Application February 23, 1934, Serial No. 712,601

14 Claims. (Cl. 221—62)

This invention relates to container closures, and among the objects of the invention is to provide a closure that is efficient in operation, economical to manufacture, easy to manipulate and which has no detachable parts to become mislaid, lost or inconvenient to handle.

Another object of the invention is to provide a self-contained closure made of flexible material and so arranged that flexing of the same will open and close the opening of the closure.

A further object is to provide a closure member that may be easily and quickly stamped out of flexible material and folded and secured in proper shape, and provided with means for opening and closing the dispensing opening therein.

A still further object is to provide means for detachably securing the parts in position to hold the closure in closed position.

Another object is to provide a detachable seal for sealing the opening of the closure until it is desired to dispense the contents of the container.

A further object is to provide a closure for containers, which closure is made of flexible material and formed with a region of greater flexibility so arranged that the opening of the closure may be opened and closed by flexing the region of greater flexibility and the material of the closure.

A still further object is to provide a closure member having a pair of lips which may be opened and closed by flexing the material of the closure.

Other objects, advantages and capabilities will later more fully appear.

My invention further resides in the combination, construction and arrangement of parts illustrated in the accompanying drawings, and while I have shown therein preferred embodiments of my invention I wish it understood that the same are susceptible of modification and change without departing from the spirit of this invention.

40 In the drawings:—

Fig. 1 is a perspective view of one form of closure embodying my invention.

Fig. 2 is a transverse section taken on the line 2—2 of Fig. 1.

45 Fig. 3 is a view similar to Fig. 2, taken on the line 2—2 of Fig. 1, but extended downwardly to include the fulcrum pin 1, as shown by the continuation of said line 2—2 downwardly in dotted lines. Fig. 3 also shows an inner protective sheet to protect the pins from deterioration by the contents of the container.

50 Fig. 4 is a view of the inner side of a blank stamped out to form my container and just prior to its being folded into the shape shown in Fig. 1.

55 Fig. 5 is a detail elevation of means for locking

the closure in closed position, as viewed from the line 5—5 of Fig. 2.

Fig. 6 is a detail sectional view of means for permitting the overlapping parts to slide with relation to each other.

Fig. 7 is a perspective view of the detail and associated parts shown in Fig. 6.

Fig. 8 is a perspective view of the closure of Fig. 1, but showing the same in closed position.

Fig. 9 is a fragmentary plan view of a portion 10 of the blank for forming a modified form of closure embodying my invention and prior to its being folded into final position.

Fig. 10 is a sectional view taken on the line 10—10 of Fig. 9 after the parts of Fig. 9 have been 15 folded into final position.

Fig. 11 is a fragmentary view of the upper portion of a closure embodying the form of Figs. 9 and 10.

Fig. 12 is a view similar to Fig. 11 but showing 20 the parts detachably secured in position for holding the closure in closed position.

Fig. 13 is a plan view of a blank stamped out and just prior to being folded into position to form another modification of my invention.

Fig. 14 is a perspective view of a closure formed by folding into shape the blank of Fig. 13, but showing means applied for locking the closure in closed position.

Fig. 15 is a view similar to Fig. 14, but showing 30 the closure open and in position for dispensing the contents of the container.

Fig. 16 is a section taken on the line 16—16 of Fig. 15 and looking in the direction of the arrows.

Fig. 17 is a fragmentary transverse section 35 taken on the line 17—17 of Fig. 14, but showing the parts in position when the closure opening is open.

Fig. 18 is an enlarged transverse section taken through the lips forming the opening of the closure, and showing these lips in closed position and having a seal applied thereto, which may be torn loose when the lips are moved to open position.

Fig. 19 is a view similar to Fig. 18, but showing the lips after being moved to open position, and 45 just prior to tearing loose of the seal.

Fig. 20 is a view similar to Fig. 19, but showing the seal torn loose from the lips.

Fig. 21 is a fragmentary perspective view of the upper portion of another form of my closure 50 and showing a further means for opening and closing the lips.

Fig. 22 is a transverse section on the line 22—22 of Fig. 21.

Referring in detail to the drawings, and more 55

particularly to the form of my invention shown in Figs. 1 to 8, inclusive, my improved closure 2 may be applied in any desired manner to a container 3 which, as will be obvious, may be of any desired shape.

The blank 4 (see Fig. 4) is stamped to the desired shape and is provided with the extending portions 5 and 6 and the slots 7, 8, 9 and 10. Also secured to the marginal edges of the extended portion 6 is a strip 11 of cork or other desired material to assist in sealing the joint when the blank is folded into final shape. This blank is also provided with the openings 12 and 13, for a purpose which will hereinafter be more clearly seen. This blank 4 is then bent into conical shape as shown in Fig. 1. The operating pin 14, which is provided with a finger piece 15, is inserted through the intersecting portions of slots 7 and 8 (as shown in Figs. 1 and 2), there also being applied around the edges of these slots the reinforcing strips 16 and 17. There is also secured to the inner head 18 of the pin 14 a fastening element 19 of the shape shown in Fig. 5, which rotates with pin 14 and is formed with a hook portion 20 and slot 21, which hook when the pin has been moved to the upper end of the two slots 7 and 8 takes over a headed pin 22, which pin upon rotation of the element 19 is caused to engage in slot 21 so as to hold the lips 23 and 24 together in close relation to each other to close the opening 25, as shown in Fig. 8.

In the form shown in Figs. 2 and 3 pins 26 and 27, after the blank has been folded into conical form, are passed through openings 12 and 13, respectively, and also through slots 9 and 10, respectively, which pins are provided with suitable heads to prevent their being withdrawn from these openings and slots. When the pin 14 is moved longitudinally in slots 7 and 8 the overlapping extensions 5 and 6 will have a certain amount of sliding movement with relation to each other, which is provided for by pin 26 sliding in slot 9 and pin 27 sliding in slot 10, thus facilitating the flexing of the body portion of the closure 2 sufficiently to permit opening and closing of lips 23 and 24, and will hold the overlapping portions in engagement sufficiently close to prevent leakage of the contents of the container.

It should also be pointed out that when the blank 4 is folded into substantially conical shape openings 28 and 29 will fall into registry with each other, and through which openings will be inserted and secured the fulcrum pin 4, shown in Fig. 3, this pin serving as a fulcrum for the overlapping portions of the body portion of the closure to permit the sliding upon each other of these overlapping portions. These openings 28 and 29 may be reinforced with strengthening pieces 31 and 32, as shown in Fig. 3.

From the above it will be readily apparent that when the operating pin 14 is moved to the bottom of the intersecting slots 7 and 8, lips 23 and 24 will be spread apart to open the opening 25 therebetween. When operating pin 14 is moved to the top end of slots 7 and 8 these top ends will be drawn together from their positions shown in Fig. 1 to cause lips 23 and 24 to close to the position shown in Fig. 8, which will close the opening 25. This movement is possible because of the flexible nature of the material from which closure 2 is made, which material may consist of paper, or other fibrous material, thin metal, celluloid, as well as lead or other ductile material capable of a bending movement. I do not wish this invention to be limited to any specific material, but comprehend the use of any material that will

adapt itself to the closing and opening of lips 23 and 24 in the manner stated above. Also, as stated above, rotation of pin 14 upon its reaching the top travel of the slots 7 and 8 will fasten the parts together because of engagement of hook 20 over pin 22 in the manner already stated.

As shown in Fig. 3, a protective lining 33 may be secured to the inside of extension 6 and the body portion of closure 2 by gluing or otherwise, to protect the inner heads of pins 14, 26, 27 and 1 from deterioration should the contents of the container be such as to otherwise cause deterioration of these portions.

Instead of using pins 26 and 27 for holding together in slidable engagement overlapping extensions 5 and 6, the form shown in Figs. 6 and 7 may be used, which consists in fastening to extension 5 the element 34, which may be of metal, celluloid or any other material of suitable rigidity, having the portion 35 passing through the slot 9 and formed on the inside with the extension 36 for sliding engagement with the adjacent interior surface of the conical body portion. A similar means may be provided for sliding movement in slot 10 on the opposite side of 25 the elongated slots 7 and 8.

In Fig. 9 I have shown another form of my invention, which is the preferred form, and which consists of a blank 37 (only a portion of the blank being shown, that portion omitted 30 being plain and forming the balance of a blank necessary to bend into the shape of a cone) stamped into the shape shown, the stippled portions of which indicate surfaces to be glued. In this form, and assuming the blank to be bent 35 into substantially conical shape, the edge *a* will be passed underneath the surface 38 to a distance indicated by the dotted line *a'*, which will cause line *b* to register with line *b'* and line *c* to register with line *c'*, the glue on the upper 40 surfaces, represented between lines *a* and *c*, contacting with and adhering to the under surface of that portion represented between the lines *a'* and *c'*. While I have referred to glue, my other suitable fastening means may be used for 45 securing these surfaces together.

The finger piece 39 is then bent downwardly and away from the eye, as viewed in Fig. 9, along the line *b'*, and again upwardly along the line *e*, and this upwardly extending portion being glued or otherwise fixed to the downwardly extending portion. This upwardly extending portion is then bent downwardly and away from the eye, as viewed in Fig. 9, along the line *f*, and the material forming this conical body is 55 bent downwardly along the line *b*—*b'* and the line *d*, after the manner shown in Fig. 10, so that the portion along the line *c*—*c'* will form the bottom of an inwardly extending depression, the parts forming the same being of flexible 60 material.

The portions 40 and 41 are also bent inwardly and the tab 42 bent upwardly toward the eye, as viewed in Fig. 9, the portions 43 and 44 being glued together, with the outwardly extending tab 42 being glued therebetween and extending outwardly of the cone, as shown in Fig. 11, which figure also illustrates the outwardly extending finger piece 39, which is provided with an opening 45 adapted to be snapped into position over pin 46 to detachably hold finger piece 39 in closed engagement with the material of the cone after the manner shown in Fig. 12.

The position of the finger piece 39, as shown in Fig. 11, corresponds substantially to that 75

shown in Fig. 10, at which time the portions of the pleat or creased region will hold the lips 47 and 48 (see Fig. 11) in separated position, while when the finger piece 39 is moved into the position shown in Fig. 12 these lips will be moved tightly together, as shown in this latter figure. These lips 47 and 48 in this form of my invention correspond in function and operation to the lips 23 and 24, shown in the form illustrated in Fig. 1.

Due to the portions 43 and 44 being glued together, with the tab 42 bent therebetween to extend outwardly, as shown in Fig. 11, I have provided a seal for the opening between lips 47 and 48, which will seal the contents of the container therein until finger piece 39 is moved from the position shown in Fig. 12 to the position shown in Fig. 11, after which the seal may be removed by grasping the tab 42 with the hand and pulling upon it to tear loose the portions 43 and 44 and the portions 40 and 41 attached thereto, which will then expose the opening between lips 47 and 48 for removal of the contents of the container. This is more clearly understood from an inspection of Figs. 18, 19 and 20, in which Fig. 18 shows the lips 47 and 48 closed with the detachable seal therebetween and the tab 42 projecting outwardly; Fig. 19 showing the tab 42 still connected to portions 40, 41, 43 and 44 just prior to being torn loose by pulling outwardly upon tab 42; while Fig. 20 shows this seal as having been torn loose and removed to expose the opening between lips 47 and 48 ready for dispensing of the contents of the container, this being effected by tearing the portions 40 and 41 loose from the lips 47 and 48 and the body portion of the closure member. The opening between lips 47 and 48 is then available for use in dispensing the contents of the container and may be opened and closed by moving the finger piece 39 in one direction or the other as described above.

It is here pointed out that instead of using the opening 45 and pin 46 the finger piece 39 may be secured closely in contact with the closure member by any other suitable means desired, and may be temporarily fastened in such position by a spot of glue which may be torn loose when it is desired to dispense the contents of the container. In such latter instance the pin 46 would represent a spot of glue and the opening 45 would be omitted from the finger piece 39, which latter member would be merely pushed downwardly against the spot of glue.

It will thus be seen that the bending inwardly of the portions along the lines *b*—*b'*, *c*—*c'* and *d*, thus afford a region of greater flexibility, which flexibility may, if desired, be increased by adding at any number of desired spaced places along the surface of the cone, ribs 50, shown in Fig. 16. Any desired number of such ribs may be added as desired.

Another form of my invention is shown in Fig. 13, in which the meeting edges of the cone when the blank is bent into conical shape may consist of the surfaces 51, 52, which may be bent inwardly of the cone and glued together, the stippling on these surfaces representing glue, and the slots 53, 54 permitting these two surfaces to be brought into overlapping engagement, with a portion extending on the opposite side for strengthening purposes. In this form the portions 55 and 56 are bent downwardly and inwardly and glued to the inner surface.

Passing through the material of the conical

body portion is the finger piece 57, which may be of celluloid or other suitable material, this finger piece passing first through a slot 58 in the outer portion of the cone, then along the portion 59, which has been bent inwardly, and then through slot 60, and finally being glued into position between the portions 51 and 52. A string, wire or other suitable reinforcing element 61 may be passed along the adjacent portions of these elements to further insure that the finger piece 57 will not become detached from the body of the closure member. The portion 62 will be opposite the portion 59 and complete the valley or groove, thus providing a flexible portion more or less similar to that shown in Fig. 10 for the form of Fig. 9. In Fig. 13 the reinforcing strip 63 may, if desired, be glued along the outside of the cone, as shown, to reinforce these parts, and the additional reinforcing strip 64 added to the inside if desired. The form shown in Figs. 13 and 17 may also be provided with the pin 65, over the head of which the opening 66 of the finger piece 57 may be passed to hold the finger piece closely adjacent to the outer surface of the closure member.

The operation of the form shown in Figs. 13 and 17 is similar to that shown in Figs. 9, 10, 11 and 12, in that by moving the finger piece 57 away from contact with the closure member so as to open up the depression or valley between portions 59 and 62, the lips 67 and 68 will be separated to open the opening therebetween. When the finger piece is moved in the opposite direction these lips will be closed to close this opening. As a means to lock the finger piece in substantial contact with the surface of the closure member I may provide the device shown in Figs. 14, 15, 16 and 17, which comprises a member rotatable about pin 69, this rotatable member being designated at 70 and having a slot larger at one end than the other, the enlarged end being designated at 71, and when moved into registry with opening 66 (see Fig. 17) will permit passage of the finger piece over the head of pin 65, after which the rotatable member 70 will be swung on pin 69 to move the narrow portion of the slot into contact with pin 65 and under the edge of head 72 thereof, thus preventing opening of the finger piece until the rotatable member 70 is again rotated to bring the enlarged opening 71 into registry with the opening 66, after which the finger piece may be swung to open position to open the lips of the closure member.

A further modification is shown in Figs. 21 and 22, in which the conical member has the inwardly extending portions 73 and 74 with the extensions 75 and 76 glued together, the portions 73 and 74 forming a trough or depression, which upon being flexed will open or close the lips 77 and 78, depending upon the direction of the flexing movement. This flexing movement is produced by rotation of the disk or plate 79, which is provided with the cam grooves 80 and 81, which respectively engage pins 82, 83. As this plate 79 is rotated, if the rotation is such as to throw pins 82 and 83 outwardly, this will cause the members 73, 74 to be flexed away from each other to open lips 77 and 78. If, however, rotation of plate 79 is in the opposite direction so as to draw pins 82 and 83 inwardly towards each other, the flexing of parts 73 and 74 will be in the opposite direction so as to bring lips 77 and 78 together to close the opening therebetween. This plate 79 is rotated upon pin 84, which extends inwardly through the inner portion of portion 73 passing through an opening therein, which permits por-

tion 73 to move longitudinally of pin 84 to enable the flexing movement described above.

From the above the method of forming my improved closure device and its operation will be 5 clearly understood.

Having now described my invention,

I claim:—

1. A dispensing closure for containers, comprising a conical body portion having a dispensing opening adjacent its apex, said body portion being formed of flexible material and having meeting portions that overlap and are slidably related to each other, each of said overlapping portions having an elongated slot, said slots each occupying a position at an angle to the other, and a pin extending through both of said slots, said slots and pin being so arranged that movement of the pin longitudinally in the slots will open and close the dispensing opening.
2. A dispensing closure for containers, comprising a conical body portion having a dispensing opening adjacent its apex, said body portion being formed of flexible material and having meeting portions that overlap and are slidably related to each other, each of said overlapping portions having an elongated slot, said slots each occupying a position at an angle to the other, and a pin extending through both of said slots, said slots and pin being so arranged that movement of the pin longitudinally in the slots will open and close the dispensing opening, said movement of the pin in the slots flexing said body portion, and means to permit a sliding movement of the overlapping portions with relation to each other.
3. A dispensing closure for containers, comprising a conical body portion having a dispensing opening adjacent its apex, said body portion being formed of flexible material and having meeting portions that overlap and are slidably related to each other, each of said overlapping portions having an elongated slot, said slots each occupying a position at an angle to the other, and a pin extending through both of said slots, said slots and pin being so arranged that movement of the pin longitudinally in the slots will open and close the dispensing opening, and means to fasten and hold said pin against longitudinal movement in the slots when the pin is at the top of the slots, so as to prevent inadvertent opening 50 of the dispensing opening.
4. A dispensing closure for containers, comprising a conical body portion formed of flexible material and having overlapping portions each formed with an elongated slot, a pair of lips above said overlapping portions arranged to move toward and away from each other, said slots being angularly positioned with relation to each other when said lips are separated, a pin extending through said slots, said slots and pin being so arranged that movement of the pin along the slots in one direction will flex the body portion and cause said lips to move toward each other, and movement of the pin along the slots in the opposite direction will flex the body portion and cause said lips to move away from each other, whereby to open and close the opening formed between the lips.
5. A dispensing closure for containers, comprising an outwardly projecting flexible tapered body portion having an apex, a pair of lips adjacent said apex, which lips when moved apart provide an opening into the interior of the container, said lips being movable toward and away from each other, an elongated portion of the body portion in approximate alignment with said lips

being of greater flexibility than the main part of the body portion and arranged to be capable of a bending movement to move said lips toward and away from each other, and means for flexing the elongated portion of greater flexibility to open and close said lips.

6. A dispensing closure for containers, comprising an outwardly projecting flexible tapered body portion having an apex, a pair of lips adjacent said apex, which lips when moved apart provide an opening into the interior of the container, said lips being movable toward and away from each other, an elongated portion of the body portion in approximate alignment with said lips being of greater flexibility than the main part of the body portion and arranged to be capable of a bending movement to move said lips toward and away from each other, and means for flexing the elongated portion of greater flexibility to open and close said lips, said elongated portion 10 of greater flexibility being substantially triangular in shape when said lips are open.

7. A dispensing closure for containers, comprising an outwardly projecting flexible tapered body portion having an apex, a pair of lips adjacent said apex, which lips when moved apart provide an opening into the interior of the container, said lips being movable toward and away from each other, an elongated portion of the body portion in approximate alignment with said lips being of greater flexibility than the main part of the body portion and arranged to be capable of a bending movement to move said lips toward and away from each other, and means for flexing the elongated portion of greater flexibility to open and close said lips, said elongated portion 20 of greater flexibility being substantially triangular in shape when said lips are open, said means comprising a finger piece extending outwardly from said body portion and secured to the portion of 30 greater flexibility, so that movement of the finger piece will flex the portion of greater flexibility.

8. A dispensing closure for containers, comprising an outwardly projecting flexible tapered body portion having an apex, a pair of lips adjacent said apex, which lips when moved apart provide an opening into the interior of the container, said lips being movable toward and away from each other, an elongated portion of the body portion in approximate alignment with said lips being of greater flexibility than the main part of the body portion and arranged to be capable of a bending movement to move said lips toward and away from each other, and means for flexing the elongated portion of greater flexibility to open and 40 close said lips, said elongated portion of greater flexibility being substantially triangular in shape when said lips are open, said means comprising a finger piece extending outwardly from said body portion and secured to the portion of greater 50 flexibility, so that movement of the finger piece will flex the portion of greater flexibility, and means for holding said finger piece close to said body portion for holding said lips close together.

9. A closure for containers, comprising a substantially conical flexible body portion, a pair of lips adjacent the apex of the conical body portion adapted when spread apart to define an opening into the interior of said body portion, and when drawn together to close said opening, 70 an elongated portion of the body portion in substantial alignment with said opening being formed with a creased portion to provide a region the edges of which are in substantial alignment with the free edges of said lips, and a finger piece 75

secured to the creased portion so that movement of the finger piece in one direction will flex the creased portion to open said lips and movement in the opposite direction will close said lips.

5 10. A closure for containers, comprising a substantially conical flexible body portion, a pair of lips adjacent the apex of the conical body portion adapted when spread apart to define an opening into the interior of said body portion, and when drawn together to close said opening, an elongated portion of the body portion in substantial alignment with said opening being formed with a creased portion to provide a region the edges of which are in substantial alignment with the free edges of said lips, and a finger piece secured to the creased portion so that movement of the finger piece in one direction will flex the creased portion to open said lips and movement in the opposite direction will close said lips, and means to fasten said finger piece closely adjacent the surface of the cone to hold the lips closed.

15 20. A closure for containers, comprising a substantially conical flexible body portion, a pair of lips adjacent the apex of the conical body portion adapted when spread apart to define an opening into the interior of said body portion, and when drawn together to close said opening, an elongated portion of the body portion in substantial alignment with said opening being formed with a creased portion to provide a region the edges of which are in substantial alignment with the free edges of said lips, and a finger piece secured to the creased portion so that movement of the finger piece in one direction will flex the creased portion to open said lips and movement in the opposite direction will close said lips, and a removable covering of rendible material secured to said lips to seal the opening therebetween to form a seal until the contents of the container are to be withdrawn, at which time said removable covering may be torn away.

25 30. A closure for containers, comprising a substantially conical flexible body portion, a pair of lips adjacent the apex of the conical body portion adapted when spread apart to define an opening into the interior of said body portion, and when drawn together to close said opening, an elongated portion of the body portion in substantial alignment with said opening being formed with a creased portion to provide a region the edges of which are in substantial alignment with the free edges of said lips, and a finger piece secured to the creased portion so that movement of the finger piece in one direction will flex the creased portion to open said lips and movement in the opposite direction will close said lips, and a removable covering of rendible material secured to said lips to seal the opening therebetween to form a seal until the contents of the container are to be withdrawn, at which time said removable covering may be torn away, and a tab extending outwardly from said removable covering to facilitate tearing it away when desired.

40 45. 12. A closure for containers, comprising a substantially conical flexible body portion, a pair of

5 lips adjacent the apex of the conical body portion adapted when spread apart to define an opening into the interior of said body portion, and when drawn together to close said opening, an elongated portion of the body portion in substantial alignment with said opening being formed with a creased portion to provide a region the edges of which are in substantial alignment with the free edges of said lips, and a finger piece secured to the creased portion so that movement of the finger piece in one direction will flex the creased portion to open said lips and movement in the opposite direction will close said lips, and means to fasten said finger piece closely adjacent the surface of the cone to hold the lips closed.

10 15. 13. A closure for containers, comprising a substantially conical flexible body portion, a pair of lips adjacent the apex of the conical body portion adapted when spread apart to define an opening into the interior of said body portion, and when drawn together to close said opening, an elongated portion of the body portion in substantial alignment with said opening being formed with a creased portion to provide a region the edges of which are in substantial alignment with the free edges of said lips, and a finger piece secured to the creased portion so that movement of the finger piece in one direction will flex the creased portion to open said lips and movement in the opposite direction will close said lips, and a longitudinally extending rib formed in the conical body portion on a line removed from the said creased portion to increase the flexibility of said body portion.

20 25. 30. 35. 40. 45. 14. A closure for containers comprising a flexible body portion having an apex and a pair of lips adjacent said apex to define an opening when moved apart, means for flexing the body portion to cause the lips to move towards and away from each other, each of said lips having a foldable portion attached to it, each of said foldable portions having a portion to receive fastening means, said latter portions being fastened together to seal the opening, and a tab secured to said latter portions and protruding outwardly from between the lips for tearing away the parts sealing the opening between the lips when desired to dispense contents of the container.

HAROLD B. HEMB.
